H. B. MARSHALL

CARBON PILE RHEOSTAT

Filed Feb. 4, 1924

Inventor.
Harry B. Marshall
by
Albert J. Reith, Attorney

UNITED STATES PATENT OFFICE.

HARRY B. MARSHALL, OF ST. LOUIS, MISSOURI.

CARBON-PILE RHEOSTAT.

Application filed February 4, 1924. Serial No. 690,428.

To all whom it may concern:

Be it known that I, HARRY B. MARSHALL, citizen of the United States, residing at St. Louis, Missouri, have invented certain new and useful Improvements in a Carbon-Pile Rheostat; and I do hereby declare the following to be a full, clear, and exact description of the invention, such as will enable others skilled in the art to which it appertains to make and use the same.

My invention relates to rheostats of the general class in which the resistance is varied by compression, as for example by compressing a pile of carbon resistance disks.

Viewed in one of its general aspects, my invention aims to provide a cheaply manufactured, compact and highly effective rheostat of this general type, aims to provide an assembly adapted to be supported from one end and one which will have a large share of the operating portions securely housed to guard against tampering with the same, and aims to provide a rheostat particularly adapted for use with relatively small currents.

In another aspect, my invention aims to provide a rheostat construction in which a cheap and simple assembly will insure adequate electrical connections between various elements and also adequate insulation where the same is needed. Furthermore, my invention aims to provide a rheostat assembly in which a spring is employed both for carrying the current to one end of the compressible resistance, for continuously maintaining a predetermined minimum pressure on this resistance, and for reducing the effect of the adjustable pressure-producing member so as to require a relatively greater movement of the latter for a given adjustment, thereby affording a decidedly increased sensitiveness of the regulation. In this connection, my invention also aims to utilize the spring to compensate for irregularities in the dimensions of compressible resistance elements assembled in a stack, aims to apply the pressure axially of the stack and aims to provide simple means for limiting the compression of the spring.

In still another aspect, my invention aims to provide simple means for making the circuit connections to the resistance unit; also for affording an indication which will readily permit a given compression of the resistance to be duplicated. It also pro-

vides a rheostat which can readily be attached to a supporting panel so as to be supported entirely from its head end, and one which is effectively sealed to guard against tampering. Furthermore, my invention provides highly desirable features of construction and arrangement, together with other and more detailed objects will appear from the following specification and from the accompanying drawings. In the drawings,

Fig. 1 is a perspective view of a rheostat embodying my invention.

Fig. 2 is an enlarged central and longitudinal section through the same, showing this rheostat as attached to a supporting wall, such as a portion of the front panel of a radio receiving outfit.

Fig. 3 is a central and longitudinal section through an embodiment having a somewhat different casing construction and a different form of presser block.

Fig. 4 is a central and longitudinal section through still another embodiment, namely one including a shell of insulating material.

Fig. 5 is a fragmentary section showing (in a somewhat exaggerated view) how the compressible-thrust transmitting means compensates for irregularities in the dimensions of the elements which constitute the resistance pile.

In one of its immediate commercial embodiments, my invention is particularly adapted for embodiment in rheostats adapted to be attached to the panels of radio receiving sets and to be connected in series with the battery current for a vacuum tube. I am therefore illustrating and describing my invention in such an embodiment, although I do not wish to be limited to the employment of any of its novel features for any particular commercial purpose.

Referring first to the embodiments of Figs. 1 and 2, these show a carbon pile rheostat having a metal casing in the form of a tube enlarged in diameter adjacent to its forward end so as to afford a cylindrical shank portion 2 which extends through a corresponding bore in the insulating panel 3 of the radio receiving set or other apparatus in connection with which the rheostat is employed. This cylindrical shank portion 2 of the casing terminates in a head 4 adapted to bear against the forward face of the panel 3 so as to be clamped against the lat-

ter by a nut 5 threaded on the rearward portion of the said shank 2.

The enlarged forward head portion of the casing as thus constituted by the shank 2 and the head 4 is provided with a threaded bore axial of the casing for receiving a compressing screw 6 which normally has its pointed tip projecting into the considerably larger bore of the rear or main portion of the metal casing. This main bore portion of the casing is provided with an insulating lining, here shown as consisting of an insulating tube 7, an insulating washer 8 at the forward end of the bore, and an insulating bushing 9 which has its head disposed in the rear end of the bore and which has a shank projecting through the perforated rear end 10 of the casing. Extending through the bore of this shank of the bushing is the threaded stem 11 of a metal thrust receiving member which has its head 12 within the insulating lining of the casing and engaging the head of the bushing 9.

Stacked against this thrust receiving member 12 is a pile of resistance blocks 13, desirably in the form of carbon disks of a size freely fitting the bore of the insulating lining 7, the forward end of this pile being engaged by the head 14 of a presser block, while another presser block 15 has a forwardly directed head engaged by the pointed tip of the screw 6. Interposed between the heads of the presser blocks 14 and 15 is a spiral compression spring 16 which spring 35 transmits the thrust of the screw over one presser block to the other, so that the two presser blocks and the spring combine in affording resilient and compressible thrust transmitting means. The forward presser 40 block preferably has a conical cup formation engaging the screw and of a wider angle than the point of the screw, so that this presser block may rock about the extreme tip of the screw in permitting the 45 presser block to tilt out of axial alignment with the casing when compensating for irregularities in the shaping of the spring or in the dimensions of the stack of resistance blocks at various points peripherally of the latter after the manner shown in Fig. 5. To permit of such tilting, each of the 50 presser blocks 14 and 15 has its head portion considerably smaller than the bore of the insulating lining 7. Moreover, each of these presser blocks desirably has a shank 55 portion freely entering the bore of the spring, the two shanks being directed towards each other and these shanks desirably are of such a length that they will 60 engage each other when the spring has been compressed to a predetermined extent.

To make the needed circuit connections to the two ends of the resistance unit, I 65 desirably connect one side of the circuit to the stem 11 of the thrust receiving member

12. Then I connect the other side to the metal of the casing so that current will be carried to the forward end of the resistance pile through the screw 6, the presser members 14 and 15, and the spring 16. For 70 making such circuit connections, Fig. 2 shows a terminal plate 17 having a bore into which the shank of the insulating bushing 9 extends and having a face portion bearing against the rear end 10 of the metal casing, so that one circuit wire 18 can be fastened to this terminal plate by a binding screw 19. The other circuit wire 20 is clamped between a pair of lock nuts 21 and 22 which are both threaded on the stem 11, the nut 21 being separated from the terminal plate 17 by an insulating washer 23. With the parts thus arranged, it will be evident that the nut 21 simultaneously draws the head 12 of the thrust receiving member and the bushing 9 rearwardly, and clamps the terminal plate 17 between the rear end 10 of the casing and the insulating washer 23.

In employing such a carbon pile rheostat for purposes in which a given setting of the rheostat may need to be duplicated, I 90 desirably imbed the forward head 4 of the casing in an insulating dial 24 having suitable markings 25 disposed radially thereon. Then I desirably provide the screw 6 with 95 an insulating knob 26 having an indicating groove or line 27 extending longitudinally thereof, so that this line will cooperate with the markings 25 on the dial in affording an approximate indication of the setting of the rheostat. I also desirably make the screw of such a length that the rear face of the knob 26 will engage the front of the dial 24 to limit the extent to which the screw can be moved in a pressure exerting 100 direction, thereby avoiding a possible overstraining of the parts which is important in a rheostat built in a rather small size 105 for use by amateurs.

In manufacturing such a unit, the main portion 1 of the casing initially has its rear end opening of the full size of its bore, so that the various elements normally housed by this bore can all be inserted from the rear end. When this has been done, the rear end of the original metal tube is spun over to form the end flange 10, thereby holding the contents of the tube securely in position so as to prevent any tampering 115 with the same. The unit can then be shipped with the nut 5, the terminal plate 17, insulating washer 23 and the lock nuts 21 and 22 all detached, so as to permit the ready installation of the casing through the bore in the insulating panel 2, after which 120 the said previously detached parts can readily be assembled even by an amateur.

However, while Figs. 1 and 2 show an arrangement of the parts which I have 125 found highly advantageous, I do not wish

to be limited to the various features of construction and arrangement thus disclosed, it being obvious that the same might be modified in many ways without departing either from the spirit of my invention or from the appended claims. For example, Fig. 3 shows another embodiment of my invention in which the casing has a forward end portion made of a reduced diameter so as to afford a shoulder engaging the rear face of the insulating panel 1, and in which the clamping nut 28 is threaded upon the extreme forward end of the casing and engages the forward face of the panel. The same figure also shows the circuit connections as made through two terminal plates 29 and 30 spaced by an insulating washer 31 and both clamped in position by a single nut 32 threaded on the stem 11 of the rear presser member. In this case, the insulating lining is similar to that of Fig. 1, but the spring 16 is shown as directly engaging the forward end of the resistance stack 13.

Fig. 4 shows still another embodiment, namely one in which an insulating tube connects a pair of tubular metal heads, so that the main tubular portion 1 of the metal casing as employed in the embodiments of Fig. 2 and Fig. 3 is not needed. In this case, the resistance pile 13, the spring 16 and the presser members 14 and 32 are all housed by an insulating tube 33 which has thickened end portions affording shoulders over which the mouth portions of the cup-shaped tube receiving parts of the two metal heads are spun inwardly. The forward metal head has such a cup-shaped portion 34 of larger diameter than the shank 35 of this head, so as to afford a shoulder for clamping one circuit terminal plate 36 against the rear of the insulating panel 3, while a nut 37 threaded on this shank engages the front of the panel. The rear head has a forwardly open cup-shaped portion 38 clamped over the thickened rear end of the insulating tube and has a rearwardly projecting threaded shank upon which the other circuit terminal 39 is clamped by a nut 40. This rear head also has another cup-shaped portion 41 extending forwardly into the insulating tube for wedgingly receiving the shank of the thrust receiving member 42 so as to make the needed electrical connection to this member.

With the embodiments of Figs. 3 and 4, the rheostat is attached to the panel by first inserting a portion from the rear of the panel, but in each case the major portion of the unit is sealed against tampering and the entire unit is supported from its forward end.

I claim as my invention:—

1. A rheostat comprising a pile of resistance elements, a screw in axial alinement

with the pile, a compression spring operatively interposed between the screw and the pile, and means operating through the bore of the spring for limiting the compressing of the spring by the screw.

2. A rheostat as per claim 1, in which the said means comprise a pair of presser members having heads respectively engaging the screws and the nearer end of the pile, and a spiral spring disposed between the said heads, the presser members having shanks extending toward each other within the bore of the spring and adapted to engage each other when the spring has been compressed to a predetermined extent.

3. A rheostat comprising as its sole supporting member a metal tube contracted at both ends to afford perforate heads for the tube, an insulating lining for the tube comprising a tubular portion and a pair of perforate end portions respectively engaging the inner faces of the said heads, a pile or resistance element within the tubular portion of the insulating lining, a screw threaded through one head, compressible and resilient thrust transmitting means disposed within the said tubular portion and interposed between and electrically connecting the screw and the pile, and circuit connections leading respectively to the metal tube and to the rear end of the pile.

4. A rheostat comprising as its sole supporting member a metal tube contracted at both ends to afford perforate heads for the tube, an insulating lining for the tube comprising a tubular portion and a pair of perforate end portions respectively engaging the inner faces of the said heads, a pile of resistance elements within the tubular portion of the insulating lining, a screw threaded through one head, thrust transmitting means disposed within the said tubular portion and operatively interposed between and electrically connecting the screw and one end of the pile, a circuit terminal member having a portion engaging the other end of the pile and having a shank projecting through the adjacent head of the metal tube, a second circuit terminal member engaging the the last named head of the metal tube, and means insulating the first named circuit terminal member from the metal tube and from the second terminal member.

5. For use with a supporting panel provided with a perforation, a metal tubular member having a main tubular portion insertible through the said perforation from the front of the panel and having at its forward end a head having a flange engaging the front of the panel and having a threaded bore smaller in diameter than the bore of the said main tubular portion, thereby providing a perforate forward end for the said main portion; the rear end of the said main portion being flanged inwardly to pro-

- vide a perforate rear end, insulating means lining for the said main tubular portion and its said perforate ends, a resistance pile disposed within the said lining, a terminal screw having a head disposed between the rear end of the said lining and the resistance pile and having a shank projecting through the said end, a pair of circuit terminals removably supported by the said shank, means for insulating the said terminals from each other and for insulating one thereof from the said shank and the other thereof from the said head, a screw threaded through the said bore of the forward head, thrust transmitting means interposed between the screw and the forward end of the resistance pile, and means threaded upon the metal tubular member for clamping the forward head thereof to the panel to afford a support for the entire appliance.
6. A rheostat comprising a pile of resistance elements, a casing including a tubular guide portion of insulating material housing the said pile and having a rear insulating head portion adjacent to one end of the pile, the casing also having a forward head, a screw threaded through the forward head, and a compression spring between the screw and the forward end of the pile, circuit connections to the screw and the rear end of the pile, and an insulating element associated with the forward head for limiting the expansion of the spring when the screw is retracted to a certain extent and for interrupting the circuit when the screw is retracted still further.
7. For use with a support having a perforation therein, a rheostat comprising a tube provided with heads, a compression spring and a compressible resistance disposed in tandem within the tube, one of the heads having a threaded shank extending through the said perforation and having a portion engaging one face of the support, a nut threaded on the shank and bearing against the other face of the support, a screw extending axially through the shank and arranged for exerting a compressing pressure on the spring, and indicating means associated with the screw for indicating the adjustment thereof.
8. For use with a support having a perforation therein, a rheostat comprising a tube provided with heads, a compression spring and a compressible resistance disposed in tandem within the tube, one of the heads having a threaded shank extending through the said perforation and having a portion engaging one face of the support, a nut threaded on the shank and bearing against the other face of the support, a screw extending axially through the shank and arranged for exerting a compressing pressure on the spring, and means fast on the screw and adapted to engage the dial to limit the pressure increasing movement of the screw.
9. A rheostat as per claim 7, including a graduated dial fast upon the screw for affording an indication on the dial to indicate the adjustment of the screw.
10. A rheostat including a pile of resistance disks, a screw in axial alinement with the said pile, a pair of presser blocks having oppositely directed portions respectively engaging the said stack and the screw, and a spiral spring interposed between the presser blocks, the presser blocks having stems projecting towards each other within the bore of the spring and adapted to engage each other to limit the compression of the spring by the movement of the screw in one direction.
11. A rheostat as per claim 10, in combination with an insulating housing for the said stack, spring and presser blocks, the screw and the adjacent presser block having interengaging portions permitting a rocking of the presser block about the tip of the screw and the said presser block being smaller in diameter than the bore of the insulating housing to permit such rocking.
12. A rheostat including an insulating tube, a stack of resistance disks in the rear portion thereof, a metal support for the insulating tube, the said support affording a forward head for the tube, a screw threaded through the said head into the tube, a perforated insulator adjacent to the rear of the head and through which the screw normally extends, a compression spring in the forward portion of the tube, a forward presser block disposed between the spring and the tip of the screw, and a rear presser block between the spring and the said stack, and circuit connections leading respectively to the rear end of the stack and to the metal support; the spring having such expansibility as to force the forward presser block against the said insulator when the screw is sufficiently retracted, so that the circuit can be interrupted through such retraction of the screw.

Signed at St. Louis, Missouri, February 1, 1924.

HARRY B. MARSHALL.
